UNITED STATES PATENT OFFICE

2,306,658

APPARATUS FOR PUNCHING TIE PLATES

George T. Willard, Fort Lauderdale, Fla., assignor
to The P. & M. Company, Chicago, Ill., a corporation of Delaware

Original application January 3, 1938, Serial No.
183,010. Divided and this application May 18,
1942, Serial No. 443,331

4 Claims. (Cl. 78—76)

This invention relates to an improved apparatus for punching apertures in railway tie plates.

The principal object of the invention is to provide an improved apparatus of the above character for punching tie plates to form apertures therein for receiving rail retaining clip members and to combine with said punching operations a metal extruding operation to form said apertures with under-cut recesses and to form on the top surface of the plate upwardly projecting lugs overlying said recesses.

The invention is illustrated in certain preferred embodiments in the accompanying drawing, wherein:

Fig. 1 is a view in perspective of a tie plate bar illustrating the configuration of tie plate to be punched by the specific form of apparatus herein shown.

Fig. 2 is a fragmentary sectional view of one form of die and punch member for punching a tie plate and forming an upstanding lug thereon in one preferred location.

Fig. 3 is a view similar to Fig. 2, but showing the punch in a position whereby the material of the tie plate is displaced and forced into a recess in the die to form an upstanding lug on the rail abutment rib of the tie plate.

Fig. 4 is a view similar to Fig. 3 but illustrating a different form of punch member whereby the upstanding lug formed on the rail abutment rib extends the full width of the rib.

Fig. 5 is a fragmentary illustration of a further modification of apparatus, and

Fig. 6 is a sectional view taken on line 6—6 of Fig. 5, but showing the punch member in its elevated position.

The three specific embodiments of apparatus herein shown are formed with suitable proportions for performing the desired punching and metal extruding operations on a shouldered tie plate, but the apparatus is not to be limited to the specific form of tie plate shown.

The tie plate illustrated herein for convenience is designated by the reference numeral 10. It is formed with a rail-base receiving seat spaced between upstanding ribs 11—11. The plate is preferably severed from a rolled metal bar, having the desired cross-section, by shearing the bar along line 12 to provide plates of any suitable width. The aperture forming and metal extruding operations of the present apparatus may be carried out either before or after the tie plate is severed from the tie plate bar. The said shearing operation and likewise all other punching and pressing operations hereinafter described are,

preferably, performed while the tie plate bar is relatively hot. However, the metal ordinarily used for railway tie plates is such that the shearing and punching and pressing operations contemplated by this invention can be performed after the tie plate bar has cooled. In other words, the apparatus herein shown is suitable for both hot and cold metal operations.

The apparatus shown in Figs. 2 and 3 comprises a die member 13 for supporting the tie plate 10, and a punch 14 for forming a rail clip receiving aperture 15 in the plate and thereafter so displace the metal adjacent the said aperture as to form an upstanding lug 16 (Fig. 3) on the upper surface of one of said rail abutment ribs 11 of the plate.

In order to simplify the drawing, the mechanism for operating the punch member 14 is omitted and only so much of the punch and die elements are shown as is necessary to punch the clip opening 15 at one end of the plate and to form the adjacent lug 16. It will be understood that duplicate punch members 14 will be used when the openings 15—15 at opposite ends of the plate are punched simultaneously.

The said supporting die 13 is formed with a recess 17 corresponding to the curvature of one rib 11 of the tie plate and is adapted to receive said rib when the tie plate is placed in an inverted position on the die. An opening 18 corresponding to the configuration of the lower end of the punch 14 is formed in the die at a suitable position to receive the lower end of the punch during its downward or punching movement.

A recess 19 corresponding in length and depth to the desired length and height of the lug 16 to be formed in the plate extends downwardly from the bottom wall of the recess 17 and communicates through its open side with a punch opening 18 in the die. The said recess 19, it will be observed, may vary in contour so as to correspond to the configuration of the particular shape of lug desired.

The punch 14 is formed with a preferably integral shoulder 20 adapted to form a recess 15a in the bottom of the plate and force the metal displaced thereby into the recess 19 of the die to form the said lug 16. Preferably the distance from the working end of the punch to the shoulder 20 is such that the open side of the recess 19 leading into the punching opening 18 is completely closed by the punch at or prior to the engagement of said shoulder with the bottom surface of the plate 10. The particular position of the lower end of said die 14 relative to the

bottom wall of recess 19 when the shoulder 20 moves into engagement with the bottom surface of the tie plate 10 will vary with the variations in the thickness of the tie plate. However, the distance from the lower end of the punch to the said shoulder is ordinarily made of sufficient length to function as above described when operating on plates of maximum thickness.

Referring to the modified embodiment shown in Fig. 4: The tie plate 10a corresponds to the plate 10 in general contour but the recess 19a of the die 13a extends inwardly to the vertical face 23 of the rail abutment rib 11a of the tie plate. Preferably the lower surface of the recess 19a inclines slightly downwardly and inwardly toward the said vertical shoulder 23. The portion 14a of the punch may be, and preferably is, of the same general size and contour as the portion 14 of the punch previously described but the shoulder 20a is somewhat wider than the shoulder 20 of the previous punch and is also so proportioned as to form a deeper recess in the bottom of the tie plate. The said recess in the bottom of the tie plate is made somewhat longer and deeper in the present modification so as to displace a larger amount of metal, since the metal displaced is employed to make a substantially wider lug 16a, that is to say, a lug in which the inner face thereof extends to the inner face 23 of the rail abutment rib 11a of the tie plate.

Referring now to the embodiment illustrated in Figs. 5 and 6 of the drawing: 13b designates the supporting die for the tie plate, 22 designates in dotted lines the recess in the plate for receiving the rail abutment rib 11b of the plate and 19b—19b indicate recesses in the die 13b which extend at right angles to the said recess 22 so that the spaced lugs 24—24 on the plate will extend at right angles to the said rail abutment rib 11b. The said die 13 has two spaced apart openings 18b—18b for receiving the lower ends of the punches 14b—14b. It will be observed that in this embodiment the laterally extending shoulders 20b—20b of the punches, instead of extending transversely of the rail abutment rib 11b, as illustrated in the previous embodiment, extend lengthwise of said rib.

Downward movement of the punch 14b from the position indicated in Fig. 6 toward the position indicated in Fig. 5 punches the desired size opening in one end of the tie plate. As soon as the said punches 14b—14b reach the position to close the recesses 19b—19b, the shoulders 20b—20b of the punch elements are caused to press on the bottom of the tie plate to form the recesses and to force the metal displaced into the said recesses 19b—19b.

This application is a division of my application Serial No. 183,010, filed January 3, 1938, and is also a continuation in part through said application Serial No. 183,010 of application Serial No. 98,122, filed August 27, 1936, in which the subject matter was originally disclosed as to Figs. 2, 3 and 4, but which disclosure was cancelled out of said application Serial No. 98,122 prior to the issuance of Patent No. 2,140,344 on said application.

I claim:

1. The combination with a die having a surface for the support of a tie plate and having an opening in said surface and a recess adjacent the

- opening and sloping downwardly from the lateral confines of the opening, of a punch tool mounted for movement in and out of said opening to act upon a tie plate on the seat, said tool being shaped to conform substantially with the opening, exclusive of the recess, and having a plate-engaging shoulder over the recess distant from its work-engaging end and terminating between the confines of said opening and the edge of said recess remote from the opening, the recess providing a generally downwardly and outwardly sloping, flow-arresting surface for material of the plate displaced by the shoulder in the operation of the tool.
- 5 2. The combination with a die having a seat for the support of a tie-plate and having an opening through the seat and a recess in the seat adjacent the opening, the bottom of the recess leading directly into the opening a substantial distance below the seat, of a punching tool mounted for movement into and out of said opening to act upon a tie-plate on the seat, said tool being shaped to conform substantially with the opening, exclusive of the recess, and having a plate 10 engaging shoulder over the recess and spaced upwardly from the work engaging end of the tool a distance equal substantially to at least the sum of said first distance and the thickness of the portion of the plate above the top of the recess, 15 whereby the tool substantially fills the part of said opening immediately below the recess prior to engagement of said shoulder with the plate, the recess providing a flow-arresting surface for material of the plate displaced by the shoulder 20 in the operation of the tool.
- 25 3. The combination with a die having a seat for supporting a tie plate, an opening in said seat, and a recess in the seat adjacent the opening, of a punching tool mounted for movement into and out of said opening to act upon a tie-plate on said seat, the tool having an initial, plate-engaging end shaped to conform substantially with the opening, exclusive of the recess, and also having a shoulder above said end and overlying the recess, the shoulder extending outwardly from the tool, and terminating in a gouging edge located a substantial distance inwardly from the edge of the recess remote from the tool, said shoulder being operable to gouge the surface of the plate and upset metal into said recess, and the bottom of the recess providing a flow-arresting surface for metal upset by the shoulder.
- 30 4. In an apparatus for forming tie-plate openings, the combination of a die having a seat for supporting a tie-plate and having an opening through the seat and a recess in the seat adjacent the opening, the bottom of the recess leading directly into the opening a substantial distance below the seat, means for engaging a tie-plate on the seat to punch an opening through the plate over the opening in the die, said means being shaped to conform substantially with the opening in the die, exclusive of the recess, an element operable to engage the surface of the tie-plate above the recess and movable into the plate to upset metal into the recess and indent the plate, and means for blocking said recess from the opening in the die prior to the initial engagement of said element with the plate.
- 35 5. In an apparatus for forming tie-plate openings, the combination of a die having a seat for supporting a tie-plate and having an opening through the seat and a recess in the seat adjacent the opening, the bottom of the recess leading directly into the opening a substantial distance below the seat, means for engaging a tie-plate on the seat to punch an opening through the plate over the opening in the die, said means being shaped to conform substantially with the opening in the die, exclusive of the recess, an element operable to engage the surface of the tie-plate above the recess and movable into the plate to upset metal into the recess and indent the plate, and means for blocking said recess from the opening in the die prior to the initial engagement of said element with the plate.
- 40 6. In an apparatus for forming tie-plate openings, the combination of a die having a seat for supporting a tie-plate and having an opening through the seat and a recess in the seat adjacent the opening, the bottom of the recess leading directly into the opening a substantial distance below the seat, means for engaging a tie-plate on the seat to punch an opening through the plate over the opening in the die, said means being shaped to conform substantially with the opening in the die, exclusive of the recess, an element operable to engage the surface of the tie-plate above the recess and movable into the plate to upset metal into the recess and indent the plate, and means for blocking said recess from the opening in the die prior to the initial engagement of said element with the plate.
- 45 7. In an apparatus for forming tie-plate openings, the combination of a die having a seat for supporting a tie-plate and having an opening through the seat and a recess in the seat adjacent the opening, the bottom of the recess leading directly into the opening a substantial distance below the seat, means for engaging a tie-plate on the seat to punch an opening through the plate over the opening in the die, said means being shaped to conform substantially with the opening in the die, exclusive of the recess, an element operable to engage the surface of the tie-plate above the recess and movable into the plate to upset metal into the recess and indent the plate, and means for blocking said recess from the opening in the die prior to the initial engagement of said element with the plate.
- 50 8. In an apparatus for forming tie-plate openings, the combination of a die having a seat for supporting a tie-plate and having an opening through the seat and a recess in the seat adjacent the opening, the bottom of the recess leading directly into the opening a substantial distance below the seat, means for engaging a tie-plate on the seat to punch an opening through the plate over the opening in the die, said means being shaped to conform substantially with the opening in the die, exclusive of the recess, an element operable to engage the surface of the tie-plate above the recess and movable into the plate to upset metal into the recess and indent the plate, and means for blocking said recess from the opening in the die prior to the initial engagement of said element with the plate.
- 55 9. In an apparatus for forming tie-plate openings, the combination of a die having a seat for supporting a tie-plate and having an opening through the seat and a recess in the seat adjacent the opening, the bottom of the recess leading directly into the opening a substantial distance below the seat, means for engaging a tie-plate on the seat to punch an opening through the plate over the opening in the die, said means being shaped to conform substantially with the opening in the die, exclusive of the recess, an element operable to engage the surface of the tie-plate above the recess and movable into the plate to upset metal into the recess and indent the plate, and means for blocking said recess from the opening in the die prior to the initial engagement of said element with the plate.
- 60 10. In an apparatus for forming tie-plate openings, the combination of a die having a seat for supporting a tie-plate and having an opening through the seat and a recess in the seat adjacent the opening, the bottom of the recess leading directly into the opening a substantial distance below the seat, means for engaging a tie-plate on the seat to punch an opening through the plate over the opening in the die, said means being shaped to conform substantially with the opening in the die, exclusive of the recess, an element operable to engage the surface of the tie-plate above the recess and movable into the plate to upset metal into the recess and indent the plate, and means for blocking said recess from the opening in the die prior to the initial engagement of said element with the plate.
- 65 11. In an apparatus for forming tie-plate openings, the combination of a die having a seat for supporting a tie-plate and having an opening through the seat and a recess in the seat adjacent the opening, the bottom of the recess leading directly into the opening a substantial distance below the seat, means for engaging a tie-plate on the seat to punch an opening through the plate over the opening in the die, said means being shaped to conform substantially with the opening in the die, exclusive of the recess, an element operable to engage the surface of the tie-plate above the recess and movable into the plate to upset metal into the recess and indent the plate, and means for blocking said recess from the opening in the die prior to the initial engagement of said element with the plate.

GEORGE T. WILLARD.
